UNITED STATES PATENT OFFICE.

ROBERT W. WHITEHURST, OF NORFOLK, VIRGINIA, ASSIGNOR TO THE
R. W. WHITEHURST COMPANY, OF SAME PLACE.

DESIGN FOR A HANDLE FOR LAWN-ROLLERS.

SPECIFICATION forming part of Design No. 34,075, dated February 12, 1901.

Application filed January 18, 1901. Serial No. 43,810. Term of patent 14 years.

To all whom it may concern:

Be it known that I, ROBERT W. WHITEHURST, a citizen of the United States, residing at Norfolk, in the county of Norfolk and State 5 of Virginia, have invented and produced a new and original Design for a Handle for a Lawn-Roller, of which the following is a specification.

Reference is to be had to the accompanying 10 drawing, in which the figure illustrates a perspective view of the handle embodying the design.

As shown in the drawing, the reach A of the handle extends in a straight direction and 15 is provided with rectangular upper and lower ends a a' and an upper and a lower round portion b b' , separated a little below the middle of the reach by a rectangular portion c . A cross-bar appears at the upper end of the reach 20 and is provided with a middle rectangular portion d and two oppositely-extending bulb-like hand-grasps e . From opposite sides of

the middle rectangular portion c of the reach A two brace-bars f extend outwardly in a downwardly-oblique direction for about half 25 of their length, whence they extend downward approximately parallel with the said reach, and in the lower end of each bar appear two apertures g , and two brace-bars h extend from about the middle of the bars f 30 to the lower rectangular end a' of the reach, at right angles to the latter.

The handle shown and described is intended for a roller used in rolling lawns and similar places. 35

I claim—

The design for a handle for a lawn-roller herein shown and described.

In testimony whereof I affix my signature in the presence of two witnesses.

ROBERT W. WHITEHURST.
